UNITED STATES PATENT OFFICE.

AUSTIN R. DODGE, OF SCHENECTADY, NEW YORK, ASSIGNOR TO GENERAL ELECTRIC COMPANY, A CORPORATION OF NEW YORK.

NOZZLE-PLUG.

1,192,761.

Specification of Letters Patent. Patented July 25, 1916.

Application filed May 1, 1914. Serial No. 835,692.

To all whom it may concern:

Be it known that I, AUSTIN R. DODGE, a citizen of the United States, residing at Schenectady, in the county of Schenectady, 5 State of New York, have invented certain new and useful Improvements in Nozzle-Plugs, of which the following is a specification.

The present invention relates to nozzle 10 plugs for use in flow meters for creating a pressure difference which varies with variations in the rate of flow of the fluid being metered. These nozzle plugs, as is well known, operate on the principle of the Pitot 15 tube.

One object of my invention is to provide a nozzle plug in which the reservoirs, now commonly placed in the piping connecting the nozzle plug and the manometer for 20 maintaining more nearly constant the static pressure heads, are located directly in the base of the plug itself.

A further object is to provide such a plug 25 having a single set of leading-in openings and which is designed so that it may be adjusted for metering fluid in a pipe, no matter at what angle the pipe extends, or in which direction the flow may be.

A still further object is to provide a nozzle 30 plug which may be readily taken apart for cleaning in case it becomes clogged.

These and other objects of my invention, as well as the novel features of structure, 35 will appear from the following specification, wherein I have described a certain specific embodiment of my invention.

In the drawings, Figure 1 is a longitudinal sectional view through a nozzle plug illustrating one form which my invention 40 may take, the section being taken in a horizontal plane; Fig. 2 is an end elevation looking toward the right in Fig. 1; and Figs. 3 and 4 are views similar to Fig. 1 showing other forms of my invention.

In carrying out my invention I form the base of the plug in two parts or sections. One of these sections carries the leading and trailing tubes. In the other section are 45 formed two reservoirs into the base of which connect the leading and trailing pipes which transmit the pressures from the leading and trailing tubes to the manometer. The two sections are constructed to be firmly fastened together, the fastening means being

such that the sections may be readily taken 55 apart and also such that one section may be turned relatively to the other, so as to bring the reservoirs into the correct position as related to the leading and trailing tubes for any particular pipe to which the nozzle plug 60 is to be attached. When connected together, the leading and trailing tubes of the one section will communicate with the respective reservoirs of the other section.

Referring to the drawing, Fig. 1, the base 65 of the nozzle plug is shown as being made in two sections 5 and 6. The section 5 is a tubular member having a threaded portion 7 adapted to be threaded into an opening in the conduit through which the fluid to be 70 metered flows, and a tapered projecting nipple 8. The section 6 comprises a nipple 9 having a tapered bore as at 10 adapted to receive the tapered nipple 8. These tapered surfaces coöperate to form a tight joint and 75 are pulled together and held by suitable means, as the threaded nut 11. Formed integral with the nipple 9 are the reservoirs 12 and 13, one being located on each side of the central longitudinally extending portion 80 14. This central portion has a longitudinal bore 16 connected with reservoir 13 by the passage 15. The outer end of the central portion 14 is threaded to receive the cap 17 which forms a chamber 18 at the end of the 85 plug. This chamber communicates with the reservoir 12 by the passages 19. The cap 17 has a central opening closed by a plug 17a. This plug may be removed for cleaning purposes. The section 5 carries the leading tube 90 20 in which are formed the leading orifices 21 and the trailing tube 22 in which are the trailing orifices 23. In the present instance these tubes are shown as being concentric, the trailing tube being inside the leading 95 tube and terminating in a block 23a in which are formed the orifices 23 already referred to. It will be understood, however, that the invention is not limited to this arrangement. Between the tubes 20 and 22 is an intermediate tube 24 between which and tube 22 is the passage 24a. This tube is preferably 100 carried by the base section 6. The leading tube communicates with the reservoir 13 by way of the passage 24a and the passage 15. 105 The trailing tube extends through the bore 16 into the chamber 18 thus communicating with the reservoir 12 by passage 19. A suit-

able packing 25 surrounds the tube 22 and cuts off communication between the bore 16 and the chamber 18. This packing may be held in place by the threaded cap 25^a. By 5 this arrangement it will be clear that the leading tube communicates with reservoir 13 and the trailing tube with reservoir 12. 26 and 27 are the usual pipes which connect the nozzle plug to the manometer. These pipes 10 connect into the bottoms of the reservoir. 28 are removable plugs closing openings in the top of the reservoir. These openings are used for initially filling the piping with water as is well known. In using the nozzle 15 plug, the leading orifices are made to face the flowing stream and the trailing orifices are made to extend at an angle thereto. The reservoirs must occupy a vertical position with the pipes 26 and 27 coming in at 20 the bottom. From this it is obvious that the reservoirs must occupy a position relative to the leading and trailing tubes, depending upon the angle of the pipe to which the plug is to be attached and the direction of the 25 flow. By constructing the base of the nozzle plug in two parts or sections, one of which carries the leading and trailing tube and the other the reservoirs, it will be clear that the plug may be readily adapted for 30 use in connection with a pipe extending at any angle and through which the fluid to be metered flows in either direction, it being only necessary to loosen the connector 11 and turn the two base sections relatively to 35 each other until the reservoirs occupy the desired position with relation to the openings in the leading and trailing tubes. The base section 5 is preferably provided on opposite sides with flattened surfaces 5^a, shown 40 in dotted lines, the planes of which are parallel to each other and to a plane through the center of the leading tube and its orifices. Upon these flattened surfaces are arrows or other suitable indicia for indicating 45 the direction in which the leading orifices face. In adjusting the nozzle plug in a conduit, the base section 5 will be first turned so that the flat surfaces 5^a are parallel with the conduit and the orifices face in the correct 50 direction. The base section 6 is then turned to bring the reservoirs into a vertical position. The fastening means 11 is then tightened to hold the two sections in adjusted position.

55 In Fig. 3 is shown another form of my invention in which the reservoirs are arranged in longitudinal alignment with the leading and trailing tubes. In this arrangement the one section 28 of the base carries the leading and trailing tubes 29 and 30, and the other section has formed therein the reservoirs 31 and 32. The leading tube 29 60 communicates directly with the reservoir 31. The trailing tube 30 extends through reservoir 31 and communicates with reservoir 32.

Communication between the two reservoirs is cut off by the packing 33 which surrounds the tube 30 and is held in place by a hollow threaded nut 34. Access to this nut for removing or adjusting it may be obtained by removing the plug 35 which closes an opening in the upper part of the reservoir 32.

The arrangement shown in Fig. 4 is substantially the same as that shown in Figs. 1 and 3 except that the reservoirs 36 and 37 are shown as being concentric. This arrangement is of particular advantage for use on ship-board, since as the reservoirs have a common center, the tilting of the ship will affect the static pressure heads of each reservoir by the same amount. When the conduit in connection with which the nozzle plug is used is lagged, as will ordinarily be the case with steam flow, the base section which carries the leading and trailing tubes will be 50 made of sufficient length to bring the coupling for the base sections well outside the lagging. This is illustrated in Fig. 4 where the conduit 38, through which the fluid to be metered flows, is shown as being lagged as at 40. By this arrangement the base sections and the coupling are readily accessible for adjustment. Forming the reservoirs in the base of the nozzle plug is of decided advantage in that it greatly simplifies the piping 95 arrangement between the nozzle plug and the manometer, permitting of a piping arrangement which requires fewer connections, which is more compact, and which is much more easily installed. This will be appreciated when it is considered that it is necessary that the reservoirs be at exactly the same height and be on the correct level as related to the leading and trailing tubes in order to insure accuracy in the readings of 100 the instrument.

In connection with any of the forms illustrated, it will be obvious that the nozzle plug can be readily taken apart either for cleaning or for other purposes.

In accordance with the provisions of the patent statutes, I have described the principle of operation of my invention, together with the apparatus which I now consider to represent the best embodiment thereof; but I desire to have it understood that the apparatus shown is only illustrative and that the invention can be carried out by other means.

What I claim as new and desire to secure by Letters Patent of the United States, is:—

1. In a nozzle plug, the combination of a base provided with an angular portion having reservoirs formed therein and passages communicating with them adjacent their upper ends, and means containing leading and trailing orifices carried by said base and communicating with said reservoirs through the passages, said angular portion being provided with openings which communicate 120

with the reservoirs to receive pipe connections for connecting the nozzle plug to a manometer.

2. In a nozzle plug, the combination of a base provided with an angular depending portion having two reservoirs formed therein, and tubes having leading and trailing orifices therein carried by the base and communicating with the two reservoirs at the upper end thereof, and at the same level, said depending portion having openings therein which communicate with the reservoirs to receive pipe connections for connecting the nozzle plug to a manometer.

15 3. A nozzle plug having its base formed in two sections, and leading and trailing tubes carried by one of said sections, the other of said sections having reservoirs formed therein with which said tubes communicate, said tubes communicating with said reservoirs at the upper portions thereof, said last named section being further provided with openings to receive pipe connections for connecting the nozzle plug to a manometer.

20 4. In a nozzle plug, the combination of a base formed in two sections, means for fastening the sections together, said means permitting the sections to be turned relatively to each other, means containing leading and trailing orifices carried by one of said sections, reservoirs formed in the other of said sections, and means connecting the said leading and trailing orifices to the reservoirs.

25 5. In a nozzle plug, the combination of a base section having a tapered socket, a second base section having a projecting tapered nipple which fits into said socket, reservoirs formed in one of said sections, and leading and trailing tubes carried by the other of said sections, which tubes communicate with the reservoirs.

40 6. In a nozzle plug, the combination of a base formed in two sections, means containing leading and trailing orifices carried by one of said sections, said other section being provided with openings with which the leading and trailing orifices communicate, and detachable means for fastening said sections together, said sections being adjustable relative to each other in a plane at right angles to the longitudinal axis of the plug.

45 7. In a nozzle plug, the combination with a base provided with an angular portion having concentric reservoirs formed therein and passages communicating with them, of means containing leading and trailing orifices carried by said base and communicating with the upper portions of the reservoirs through the passages therein.

50 8. A nozzle plug having its base formed in two sections one of which carries the leading and trailing tubes and the other of which has concentric reservoirs formed therein with which said tubes communicate,

the axis of said reservoirs being at an angle to the longitudinal axis of the tubes.

9. In a nozzle plug, the combination of a base formed in two sections, means containing leading and trailing orifices carried by one of said sections, concentric reservoirs formed in the other of said sections, and means connecting the said leading and trailing orifices to the reservoirs, the axis of said reservoirs being at an angle to the longitudinal axis of the tubes.

10. In an apparatus of the character described, the combination with a member adapted to be threaded into a conduit and carrying tubes containing leading and trailing orifices, of a second member comprising reservoirs adapted to be attached directly to the first named member with the tubes communicating with said reservoirs adjacent their upper ends said second member being provided with openings which communicate with said reservoirs to receive pipe connections for connecting the nozzle plug to a manometer.

15 11. In an apparatus of the character described, the combination of a member adapted to be threaded into a conduit and carrying tubes containing leading and trailing orifices, a second member comprising two reservoirs, and a single coupling for joining said two members together with the tubes in communication with said reservoirs at points adjacent their upper ends and in the same horizontal plane.

12. In an apparatus of the character described, the combination of a base member carrying tubes containing leading and trailing orifices, and means forming a pair of reservoirs adapted to be connected directly to said base member with the reservoirs extending at right angles to and in communication with said tubes.

100 13. In an apparatus of the character described, the combination of a member adapted to be associated with a conduit and carrying means for insertion thereinto for creating a pressure difference, means forming passages through which said pressure difference is transmitted, and a second member comprising reservoirs which is connected directly to and carried by said first member with said passages communicating with said reservoirs adjacent their upper ends, said second member being provided with openings which communicate with the reservoirs to receive pipe connections for connecting the nozzle plug to a manometer.

105 14. In an apparatus of the character described, the combination of a member adapted to be threaded into a conduit, and carrying means for creating a pressure difference, means forming conduits through which the pressure difference is transmitted, a second member comprising reservoirs, and coupling means for connecting said two members to-

gether with the conduits in communication with said reservoirs, said coupling means permitting the members to be adjusted relative to each other in a plane at an angle to the longitudinal axis of the nozzle plug.

15. In an apparatus of the character described, the combination of a base member carrying tubes containing leading and trailing orifices, and a second member comprising reservoirs adapted to be connected to the base member with said tubes communicating with the upper ends of said reservoirs, said second member having openings therein which communicate with the lower ends of the reservoirs and which are adapted to receive pipe connections.

16. In a nozzle plug, the combination of a base member carrying tubes containing

leading and trailing orifices, a second member comprising a pair of reservoirs, and a 20 detachable coupling for connecting said members together, with the tubes in communication with said reservoirs, said coupling permitting the members to be connected together with the reservoirs occupying different positions in a plane at an angle to the longitudinal axis of the plug whereby the 25 plug may be applied to conduits extending at different angles.

In witness whereof, I have hereunto set 30 my hand this 30th day of April, 1914.

AUSTIN R. DODGE.

Copies of this patent may be obtained for five cents each, by addressing the "Commissioner of Patents, Washington, D. C."

It is hereby certified that in Letters Patent No. 1,192,761, granted July 25, 1916, upon the application of Austin R. Dodge, of Schenectady, New York, for an improvement in "Nozzle-Plugs," errors appear in the printed specification requiring correction as follows: Page 1, line 35, strike out the article "a"; same page, line 36, for the word "embodiment" read *embodiments*; page 2, line 10, for the word "reservoir" read *reservoirs*; and that the said Letters Patent should be read with these corrections therein that the same may conform to the record of the case in the Patent Office.

Signed and sealed this 5th day of September, A. D., 1916.

[**SEAL.**]
